HEATER

Henry J. De N. McCollum, Chicago, Ill.; Thelma McCollum executrix of said Henry J. De N. McCollum, deceased

Application December 18, 1943, Serial No. 514,755

2 Claims. (Cl. 126—102)

My invention relates generally to heaters and more particularly to heaters of the sealed combustion type incorporating a novel form of heat exchanger.

It is an object of my invention to provide an improved heater of the sealed combustion type having a simple and efficient heat exchanger, which is suitable for use in heating aircraft and which may be economically manufactured.

A further object is to provide an improved heat exchanger having primary heat transfer surfaces of large area and which may be manufactured by simple manufacturing processes.

A further object is to provide an improved heat exchanger which is light in weight and which, while made of thin sheet metal, is rigid and durable.

Other objects will appear from the following description, reference being had to the accompanying drawings, in which:

Fig. 1 is a central longitudinal sectional view taken on the line 1—1 of Fig. 2;

Fig. 2 is a transverse sectional view taken on the line 2—2 of Fig. 1; and

Fig. 3 is a transverse sectional view taken on the line 3—3 of Fig. 1.

The heater comprises a sheet metal hollow cylinder 10 having a combustion air preheating tube 12 extending longitudinally therethrough and supported by flanged annular heads 14 and 16. A narrow annular baffle 18 is secured in the cylinder 10 and divides the space within the latter into a primary combustion chamber 18 and a secondary combustion space 20. The tube 12 is provided with rows of perforations 22 to permit limited flow of air into the secondary combustion space 20.

The air for primary combustion flows through the full length of the tube 12. The latter has a bend 24 formed integrally therewith and is secured to the heater casing 26 and to a pipe 28 by a suitable flanged connection 30. The pipe 28 is connected to a carburetor 32, which includes a float bowl 34 and a solenoid operated fuel valve 36. Fuel is supplied to the carburetor through a tube 38.

The combustible mixture of fuel and air supplied by the carburetor is conveyed to the primary combustion chamber 18 through an induction tube 40. The end of the tube 40 within the combustion chamber has a bend to impart a swirling motion to the mixture, as best shown in Fig. 2.

The cylinder 10 has a pair of elongated ports 42, 43 formed therein, these ports communicating with suitable passageways formed in an igniter

housing 44 which may be welded to the cylinder 10. A hot wire electrical igniter 46 of conventional construction is arranged to ignite that portion of the combustible mixture which, due to centrifugal action, tends to enter the igniter housing through port 42 and flow therefrom through port 43. The supply of energizing current for the igniter 46 may be controlled by any well known thermostatic switch completed circuit so as to be de-energized when the heater attains its operating temperature.

The heat exchanger comprises a plurality of pairs of generally cylindrical sheets 50—51, 52—53, 54—55, and 56—57. The sheet 50 has an elongated port 60 which registers with a similar port 61 formed in the cylinder 10, and is seam welded to the cylinder 10 around the ports 60, 61 so as to be air-tight.

In the manufacture of the heat exchanger by one method which may be employed, the sheet 51 may then be placed over the sheet 50 and the offset end edges of the two sheets then seam welded together to form two passageways 62, 63 (Fig. 3) for the flow of the products of combustion from the ports 60, 61 to a similar port 64 formed by registering openings in the sheets 51 and 52, these sheets being seam welded together around the port 64.

In a similar manner sheet 53 is secured to sheet 54 around a port 66, and sheet 55 is secured to sheet 56 around a port 68. Sheet 57 is welded to the casing 26 around an exhaust port 70, and a suitable thimble 72, for connection with an exhaust pipe, is welded to the casing 26.

By virtue of this arrangement of the sheets 50—51, the products of combustion will flow from the cylinder 10 to the exhaust port 70 in the directions indicated by the arrows in Fig. 3. The flow is effectively through two passageways of narrow rectangular cross section, these passageways being jointed at intervals, at the ports 64, 66, 68 and 70. Because of this arrangement the products of combustion will flow equally through the two alternative paths provided between the successive ports 60—61, 64, 66, 68 and 70, and the temperature gradients along the two alternative paths will be substantially the same.

In the construction illustrated, the successive pairs of sheets 50—51 are equally graduated in diameter so that sheets 52—53 and 56—57 are concentric with the cylinder 10, while sheets 50—51, 54—55, and the casing 26 are eccentric with respect to the cylinder 10.

Suitable brackets 74 may be provided to aid in

supporting the heat exchanger assembly in the casing 28.

The heater may have its air for combustion and the ventilating air supplied by a ram or scoop connected to a shroud 18 secured to the casing 28. The ventilating air flows longitudinally through the crescent-shaped passageways formed between the sheets 50-57 and casing 28.

The sheets 50-57 are preferably made of stainless steel in the order of .028" thick so that they will efficiently transmit the heat from the products of combustion to the ventilating air. Since these sheets present relatively large surface areas in contact with the ventilating air and heated gases, the heat exchanger may be made 10 very small and compact for any given rate of heat transfer requirement.

While I have shown and described a particular embodiment of the invention, it will be apparent to those skilled in the art that the underlying principles thereof may be employed in variations and modifications of the apparatus disclosed. I therefore desire by the following claims to include within the scope of my invention all such modifications and variations by which substantially the 25 results of the invention may be obtained by the use of substantially the same or equivalent means.

I claim:

1. A heater comprising a central cylinder forming a combustion space, means to supply a 30 fuel and air for combustion to said space, and a

5 plurality of pairs of cylindrical sheets surrounding said cylinder, each pair of sheets being joined at their ends and spaced to provide a passageway between them, and alternate pairs of said sheets being eccentrically arranged and tangentially joined to the intermediate pairs of sheets and to said cylinder, said sheets having registering ports at the places at which they are joined, thereby to provide a closed path for the flow of the products of combustion from said cylinder to the outermost pair of said sheets, with the spaces intermediate the pairs of sheets and said cylinder forming passageways for the flow of ventilating air in a direction longitudinally of said cylinder.

2. A heat exchanger comprising a plurality of pairs of cylindrical sheets surrounding one another and of progressively increasing diameters, each pair of sheets being joined at their ends and spaced to provide a passageway between them, and alternate pairs of said sheets being eccentrically arranged and tangentially joined to the intermediate pairs of sheets, said sheets having registering ports at the places at which they are joined, thereby to provide a closed path for the flow of one fluid from the innermost to the outermost pair of said sheets, with the spaces intermediate the pairs of sheets forming passageways for the flow of another fluid in a direction longitudinally of said cylindrical sheets.

HENRY J. DE N. McCOLLUM.
